UNITED STATES PATENT OFFICE.

GEORGE F. L. FOULGER AND JOHN GEORGE GLOVER, OF LONDON,
ENGLAND.

MEANS AND APPLIANCE FOR EFFECTING LIGHTING OF INCANDESCENT OR LIKE BURNERS OF STREET OR
OTHER GAS-LAMPS.

SPECIFICATION forming part of Letters Patent No. 651,708, dated June 12, 1900.

Application filed January 19, 1900. Serial No. 2,003. (No model.)

To all whom it may concern:

Be it known that we, GEORGE FREDERICK LOMBE FOULGER, residing at The Common, Upper Clapton, London, and JOHN GEORGE GLOVER, residing at 214 St. John street, Clerkenwell, London, England, subjects of the Queen of Great Britain, have invented certain new and useful Improvements in Means and Appliances for Effecting the Lighting of Incandescent or Like Burners of Street or other Gas-Lamps, of which the following is a specification.

This invention has for its object the employment of a flexible wick-tube of an oil or spirit lamp so arranged within a lamplighter's torch-frame that by a push or other movement of a rod or the like the flexible wick-tube can be projected from above the top end of the torch-frame and be allowed to fall over and above an incandescent burner for lighting the gas, the flexible wick-tube being then drawn back to be within the torch-frame, so that the lamplighter can carry the torch from lamp to lamp in the usual manner, the flexible wick-tube being projected within each lamp in succession. The flexible wick-tube is an extension from the oil-reservoir by which the torch-light is kept burning, and to insure the flexible wick-tube falling or drooping over in the proper direction when projected we purpose weighting it in any desirable manner; but if not weighted its fall over or droop can be readily adjusted over the mantle.

Our invention is shown on the annexed drawings.

Figure 1 is a part-sectional elevation of the upper end of a lamplighter's torch with the flexible wick-tube and flame-shield inclosed; Fig. 2, an exterior elevation of the same with the flexible wick-tube and flame-shield pushed out and leaning over from above the torch-frame; Fig. 3, a part-sectional elevation of the handle end of the torch, showing the handhold or slider-lug; Fig. 4, an elevation of lamplighter's torch complete, reduced scale.

A is a hollow stick; B, an oil-tank; C, a vent to same; D, a flexible wick-tube secured in screw-head E; F, a guide-cone at upper end of flexible wick-tube D; G, a burner; H,

a flame-shield secured to burner-neck I; J, a cone-shaped edge at upper part of flame-shield; K, a top cap with centrally-apertured ferrule L, fixing an asbestos cushion or guard M on the flame-shield H; P, a perforated wind-guard to protect the flame while the torch is being carried; Q, a rod connecting oil-tank B to handhold or slider R, which is to be moved up and down by hand and guided by the slot S in hollow stick A, the slider R being connected by screw-pin T to lower end of rod Q.

When the torch is carried in the ordinary way, such as for lighting open flames of street and like lamps, and where the torch-head can be put close to the burner to light the gas from the oil-flame, no motion of the slider R is necessary; but with lamps having incandescent mantles, whether surrounded by a glass chimney or left exposed, the head of the torch must be kept clear of the gas-burner during the lighting operation, the mantles being so fragile that if touched they break or drop to powder and are rendered useless as light-giving media. By our invention such gas-lamps can be lighted with safety.

To protect incandescent flames from sudden gushes of wind, the bottom of the lantern-frame is provided with a fall-down flap, which has to be raised before the torch can be inserted into the lantern, and to prevent injury to the flap and concussion to the lantern or its burner we provide our flame-shield K with an asbestos cushion M, and after the head of the torch has been passed into the lantern an upraising action on the slider R and rod Q by the lamplighter causes the flame-shield H and the flexible wick-tube D to project beyond the upper end of the torch-stick A, the weight of the flame-shield H then gradually inclining toward the middle of the lantern and over the incandescent mantle through the flexibility of the wick-tube D, as indicated at Fig. 2, the oil-tank being still within the head of the hollow stick A. The gas being on in the lantern then comes into contact with oil-flame and flashes back to light the Bunsen flame within the mantle. By a downward action on the slider R and

rod Q the oil-tank B is lowered, and also the flexible wick-tube D, which tube D slides downwardly in the head of the stick A until the cone F bears against the top edge of the stick A to incline and guide the tube D into a vertical position, the lowering being continued until the ferrule L rests upon the top edge, as indicated at Fig. 1.

What we claim, and desire to secure by Letters Patent, is—

1. In a lamplighter's torch, the combination with the hollow stick, of an oil-tank slidably mounted therein, a flexible wick-tube carried by said oil-tank, a burner attached to the upper end of said wick-tube, and means for sliding the burner and wick-tube into and out of the open end of the hollow stick, substantially as described.
2. In a lamplighter's torch, the combination with the hollow stick having an open upper end, of an oil-tank slidably mounted therein, a flexible wick-tube carried by said oil-tank, a burner attached to the upper end of said wick-tube, a guiding-cone attached to the wick-tube below the burner, and means for sliding the burner and wick-tube into and out of the open upper end of the hollow stick, substantially as described.
3. In a lamplighter's torch, the combination with the hollow stick, of an oil-tank slidably mounted therein, a flexible wick-tube carried by said oil-tank, a burner attached to the upper end of said wick-tube, a perforated shield surrounding the burner, an asbestos disk upon the top of said shield, and means for sliding the burner and wick-tube into and out of the upper end of the hollow stick, substantially as described.
4. In a lamplighter's torch, the combination with the hollow stick having an open upper end, of an oil-tank slidably mounted therein, a flexible wick-tube carried by said oil-tank, a burner attached to the upper end

of said wick-tube, an operating-rod attached at its upper end to the oil-tank and having its lower end provided with a finger-piece, whereby the burner and wick-tube may be moved into and out of the open end of the hollow stick, substantially as described.

5. In a lamplighter's torch, the combination with the hollow stick having an open upper end, of an oil-tank slidably mounted therein, a flexible wick-tube carried by said oil-tank, a burner attached to the upper end of said wick-tube, a guiding-cone attached to the wick-tube below the burner, and an operating-rod located within the hollow stick and attached at its upper end to the oil-tank and having its lower end provided with a finger-piece, whereby the burner and flexible wick-tube may be moved into and out of the upper end of the hollow stick, substantially as described.

6. In a lamplighter's torch, the combination with the hollow stick having an open upper end, of an oil-tank slidably mounted therein, a flexible wick-tube carried by said oil-tank, a burner attached to the upper end of said wick-tube, a perforated shield surrounding the burner, an asbestos disk carried by the top of said shield, an operating-rod located within the hollow stick and attached at its upper end to the oil-tank, and a finger-piece attached to the lower end of said rod, whereby the burner and flexible tube may be moved into and out of the open end of the hollow stick, substantially as described.

In testimony whereof we have hereunto set our hands in presence of two subscribing witnesses.

GEORGE F. L. FOULGER.
JOHN GEORGE GLOVER.
